UNITED STATES PATENT OFFICE.

FRED M. SMITH, OF TAFT, CALIFORNIA.

WRENCH.

1,376,295.

Specification of Letters Patent. Patented Apr. 26, 1921.

Application filed May 21, 1920. Serial No. 383,049.

To all whom it may concern:

Be it known that I, FRED M. SMITH, a citizen of the United States, residing at Taft, in the county of Kern, State of California, have invented certain new and useful Improvements in Wrenches; and I do hereby declare the following to be a full, clear, and exact description of the invention, such as will enable others skilled in the art to which it appertains to make and use the same.

This invention relates to wrenches, and more especially to the sliding adjustments thereof including a shank grip; and the primary object of the invention is to produce a wrench of this type whose jaws are adjusted by swinging the handle and locked in adjusted position by a pawl urged forward by a spring but capable of being retracted by hand when the fingers or the glove may be very dirty or greasy and no delicate operation can be performed. The need for such a wrench is often felt by workmen whose calling keeps their hands dirty, and occasions sometimes require the use of a wrench quickly so that no time is afforded in which to cleanse the hands. Moreover, wrenches are often used when the weather is extremely cold and the hands are numb. Finally, from a mechanical view-point the tool is improved by the omission of fine parts which require careful making and delicate handling.

One feature of the invention is the means for adjusting the movable jaw with relation to the fixed jaw by swinging the handle, and pawl-and-ratchet mechanism for locking the handle after it has been swung, so that subsequent movement of the handle turns the nut or other object which stands between the jaws.

Another feature of the invention is the means for filling out one jaw by the application to its face of blocks or liners, thereby adapting the wrench to nuts of various sizes while yet retaining the use of the mechanism for adjusting the movable jaw as described above.

Details are set forth below and shown in the drawings wherein:

Figure 1 is a side elevation of this entire wrench, the toothed sector and rack being indicated in dotted lines.

Fig. 2 is a perspective view of the head of the wrench and the fixed jaw.

Fig. 3 is a perspective view of the mov-

able jaw, including a liner ready to be attached thereto.

The handle 1 of this wrench is preferably hollow and may well be a tube closed at its lower end by a screw cap 2, and thus forming a receptacle for the liners yet to be described. The shank 3 is rectangular or oval in cross section, and is fixed in or attached to the upper end of the handle, or may be formed as a continuation thereof, and at its upper end it carries a sector 4 provided with teeth 5 on its edge struck around a center through which passes a main pivot 6. On the shank slides a collar 7 preferably milled on its outer face so that it may be grasped reliably between greasy fingers, and urged normally toward the main pivot by a spring 8, and the outer end of this collar carries ratchet teeth 9 on both sides of the shank, whereby this element becomes a pawl as will be explained below.

The head 10 is a relatively flat casting thicker than the shank 3 and made up of two spaced wings 11 connected across their upper edges by a top plate 12 and separated by a space or channel 13 into which extends the upper end of the shank and its sector 4, and the wings are provided with alined holes 16 for the passage of the main pivot or bolt 6, beneath and around which their edges are struck on curves producing sectors provided with ratchet teeth 19 to be engaged by the teeth 9 on the collar or pawl. Rising rigidly from and preferably formed as a part of the head is the fixed jaw 17 whose face is herein shown as milled or serrated, and as slightly dished at one point as at 18.

Slidably mounted between the wings and under the top plate 12 is a bar 22 having a rack of teeth 25 along its lower edge to engage those on the toothed sector 4, and upstanding from one end of this bar is a movable jaw 27 whose face is provided with a longitudinal dove-tailed groove 28. While the bar is guided between the top plate and the toothed sector, it is preferred to further guide it by means of a pin 20 passing transversely through the bar and with its ends movable in slots 21 through 105 the wings 11—thus constituting means for guiding the jaw 27 in its movements and for preventing its entire displacement from the head. As shown in Fig. 3, a face plate or liner 23 is provided, its forward side 110 being milled or serrated and its rear side carrying a dove-tailed tongue 24 to fit the

groove 28. With each wrench are furnished several of these liners of various thicknesses, and they may be stored in the hollow handle and may be applied selectively to the face of one of the jaws. While it is the movable jaw herein shown and described as carrying the liner, it is clear that the latter might be applied to the other jaw or possibly to both jaws without departing from the spirit of the invention, and in fact it would be possible to apply these liners to the jaw of any wrench which was provided with a proper groove to receive them. The purpose of dishing one jaw as shown at 18 is to permit the wrench to be used for pipe work and on rods that are not angular.

In the use of this wrench, let us assume that its parts are set so that when they stand as seen in Fig. 1 the jaw faces are one inch apart. Manifestly they will slip over a one-inch nut and the shank can be moved to the left to tighten it, or the wrench reversed and the shank moved to the right to loosen the nut. To apply the jaws to a larger nut, the shank must first be swung to the right which rocks the sector 4 on the main pivot and slides the bar 22 and movable jaw 27 to the left. In other words, this opens the jaws as the pawl and ratchet mechanism permits, and then when the jaws are applied to the nut and the shank moved to the left the nut is tightened; or by reversing the wrench the nut can be loosened as is understood. To apply the wrench to a nut smaller than one inch, the pawl must be disengaged from the ratchet with one hand and the shank moved to the left. This draws the jaw faces together, and when they have grasped the nut the pawl is released and continued movement to the left tightens the nut; or the wrench can be reversed or moved oppositely to release the nut. It is obvious, therefore, that the jaws will aline with the shank only when applied to a one inch nut, and the whole head will stand with its jaw opening at an angle to the shank if the nut be larger or smaller. As this is not always desirable, provision is made for avoiding it by use of the liners.

Assuming that the parts were so set that, with a half inch liner in place, the jaw faces stood one inch apart in Fig. 1. To grasp a

nut smaller than an inch, a thicker liner 55 must be substituted (as, in fact, it might have been done as described above), but to grasp a nut larger than an inch the half inch liner may now be replaced by a thinner one. And yet, even when the liners are 60 used there is the same possibility for adjusting the jaw faces by swinging the handle.

Finally, when it is desired to turn a nut which has become stuck or whose corners 65 are worn, or when it is desired to turn a round piece of work, it becomes necessary to make use of the shank grip. Either of the different means for adjusting the jaw faces to the work may be employed, but 70 now the pawl is held out of engagement with the ratchet so that a swing of the shank to the left exerts first a tendency to further contract the jaws on the work, and then a tendency to turn the latter to the 75 right—or to the left when the wrench is reversed.

In none of these operations is a fine adjustment by the fingers necessary. The change of liners can be effected by dirty 80 or greasy hands and the collar 7 can be retracted also by dirty hands, while its spring 8 moves it automatically into active position when the grasp of the thumb and finger is withdrawn.

What is claimed as new is:

In a wrench, the combination with a shank having a toothed sector around its extremity and a main pivot through its body at the center around which said sector is struck, a collar slidable on said shank and having pawl teeth on its outer end, and a spring urging said collar outward; of a head including spaced wings defining a channel inclosing said sector, the wings being mounted on said main pivot and provided with ratchet sectors to be engaged by said pawl teeth, a rigid jaw carried by said head, and a jaw movable toward and from said rigid jaw and having a bar slidable 100 through the head and provided with a toothed rack engaging said toothed sector.

In testimony whereof I affix my signature in the presence of two witnesses.

FRED M. SMITH.
